(57) **CLAIM**

The ornamental design for a surface configuration of a vehicle body, toy, and/or replica, as shown and described.

DESCRIPTION

FIG. 1 is a perspective view of a surface configuration of a vehicle body, toy, and/or replica;

FIG. 2 is a front view thereof, a rear view being a mirror image of a front view;

FIG. 3 is a top plan view thereof;

FIG. 4 is a bottom plan view thereof; and,

FIG. 5 is a left side view thereof, a right side view being a mirror image of a left side view.

The broken line showing on the drawing disclosure is for illustrative purposes only and forms no part of the claimed design.
